CLAIM

The ornamental design for a threaded ring, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a threaded ring in accordance with my design;

FIG. 2 is a top, front perspective view thereof;

FIG. 3 is a bottom plan elevational view thereof;

FIG. 4 is a bottom, rear perspective view thereof;

FIG. 5 is a front elevational view thereof;

FIG. 6 is a right side elevational view thereof;

FIG. 7 is a rear elevational view thereof; and,

FIG. 8 is a left side elevational view thereof.
